UNITED STATES PATENT OFFICE.

JOHN CHANCHUCK, OF BURLINGTON, NORTH DAKOTA.

SMOKE-STRAINER FOR PIPES.

1,254,478.

Specification of Letters Patent.

Patented Jan. 22, 1918.

Application filed June 13, 1916. Serial No. 103,401.

To all whom it may concern:

Be it known that I, JOHN CHANCHUCK, a citizen of the United States, residing at Burlington, in the county of Ward and State of North Dakota, have invented certain useful Improvements in Smoke-Strainers for Pipes, of which the following is a specification, reference being had therein to the accompanying drawing.

10 This invention relates to means for removing the nicotine from the tobacco smoke in pipes, thus removing from the smoke the evil component thereof, and at the same time producing a cool smoke, one object of the 15 invention being the provision of means removably mounted within the bowl of the pipe so that all smoke being drawn through the stem will be filtered.

A further object of this invention is the 20 provision of a simple and inexpensive device of this character and one that can be readily placed in the pipe bowl at will.

In the accompanying drawings:—

Figure 1 is a sectional view through a pipe 25 with the present device in place.

Fig. 2 is a perspective view of the device *per se*.

Referring to the drawings, the numeral 5 designates the pipe bowl, in the bottom of 30 which adjacent to the outlet 6 thereof, is a removable strainer 7.

This strainer consists of a foraminous receptacle 8, filled with cotton gauze or fiber 9, and to the upper edge of which is connected 35 the inclined annular flange 9' which depends

from the metal plate 10, which plate is provided with the upstruck nipples 11, each of which is provided with an opening 12. The nipples project sufficiently high to prevent sparks from the tobacco when low in the 40 bowl from igniting the gauze. It will be observed that the outer surface of the flange 9' engages the inner surface of the pipe bowl so as to consequently support the foraminous receptacle.

A small tube 16 is led from the device 7 and enters the outlet 6 of the pipe bowl to insure of the passage of clean filtered smoke to the outlet, and at the same time holds the device properly in the bowl.

What I claim, as new, is:—

A smoke strainer for pipe bowls including a foraminous receptacle for insertion in the pipe bowl, smoke filtering material arranged within the receptacle, a plate, an inclined 55 annular flange depending from the outer edge of the plate and surrounding the upper edge of the receptacle for establishing a connection therebetween and arranged so as to engage the inner surface of the bowl of the 60 pipe for removably supporting the receptacle, nipples projecting upwardly from the plate and terminating in openings, and a small pipe leading from the bottom of the receptacle for communicating with the outlet 65 of the bowl for assuring of the passage of cool filtered smoke therethrough.

In testimony whereof I affix my signature.

JOHN CHANCHUCK.
